PROTECTIVE INSULATION FOR LINEMEN

Russell M. Evans, Carrollton, Ohio, assignor to
The Surety Rubber Company, Carrollton, Ohio,
a corporation of Ohio

Application June 23, 1941, Serial No. 399,254

2 Claims. (Cl. 227—27)

The invention relates to insulation for electric linemen, and more particularly to a complete insulation for the linemen's feet, as well as the climbers ordinarily worn for climbing poles, and the present invention is an improvement over my copending application Serial No. 364,854, filed November 8, 1940.

There is a constant hazard to linemen when working upon poles, repairing or replacing lines thereon, as should any portion of the lineman's body come in contact with a live wire the circuit will be instantly completed through the lineman's body, to ground through his feet or climbers which are necessarily in contact with the pole.

Means have been provided for insulating the climbers, and even for insulating the side of the lineman's foot next to the pole, and while such devices have reduced the hazard to linemen, yet contact of the outer side of the foot with the pole, or a guy-wire or live wire thereon may cause a circuit to be completed through the body, resulting in electrocution.

Consequently it is a primary object of this invention to entirely overcome all such hazards by providing complete insulation for the lineman's feet as well as his climbers, from the pole and any guy-wires or live wires connected thereto.

Another object is to provide an insulation jacket for the climbers, of the type disclosed in my co-pending application above referred to, in combination with a special type of overshoe to be worn therewith, so as to completely insulate the feet and legs of the lineman.

A further object is to provide a special type of overshoe having flaps for covering both sides of the lineman's ankle, and held securely in place by the usual foot strap upon the climber.

A still further object of the invention is to provide such a combination insulation jacket and overshoe for entirely insulating the lineman's feet and legs from the climber.

The above objects together with others which will be apparent from the drawing and following description, or which may be later referred to, may be attained by constructing the improved insulation jacket and overshoe in the manner illustrated in the accompanying drawing, in which

Figure 1 is a rear elevation of a lineman's leg and foot, showing the manner in which the insulation for the climber and the improved overshoe are worn to completely insulate the lineman's foot and leg from the climber;

Fig. 2, a fragmentary inner side elevation of the same; and

Fig. 3, a detached perspective view of the improved overshoe.

Similar numerals refer to similar parts throughout the drawing.

5 The protective insulation to which the invention pertains is designed to be applied to a lineman's climber of usual and well known form comprising a shank portion 10, having the usual stirrup 11 at its lower end, and provided with the conventional spur 12 adjacent to said stirrup.

The climber is provided with the usual leg strap loop 13 at the upper end of the shank, for connection of the leg strap 14, for attaching the climber to the lineman's leg below the knee, in 15 usual and ordinary manner, and with the loop 15, upon the stirrup for connection of the usual ankle strap 16, which is ordinarily located around the lineman's ankle.

The insulation jacket for the climber is the 20 same as disclosed in my co-pending application Serial No. 364,854, above referred to, and as shown is formed of a single unit, preferably of pure rubber or other suitable flexible insulation material of proper thickness to effectively insulate the climber against such electric circuits as the lineman may encounter.

The safety jacket is indicated generally at 17 and is of tubular shape, preferably flat in cross section so as to conform to the shape of the shank 10 of the climber, the upper end of the jacket being closed as indicated at 18 and the length of the jacket being such as to extend from the top of the shank to a point near the lower end of the spur 12, as best shown in Figs. 1 and 2. Thus, the entire shank is enclosed by the insulation jacket from the top to the spur 12.

As shown in Fig. 1 the lower open end of the insulation jacket extends over the greater portion of the spur 12 and the adjacent portion of 40 the stirrup of the climber, and the rubber is sufficiently resilient to permit the jacket to be stretched thereover as shown in said figure.

In order to accommodate the loop 13, at the 45 upper end of the shank portion of the climber, the jacket may be slit as indicated at 19 by placing two spaced parallel cuts in the outer side of the jacket so that the intervening web 20 of rubber between said slits may cover the loop 13.

In order to completely insulate the lineman's 50 feet and legs from the climbers, heavy rubber overshoes as indicated generally at 21 are worn with the insulation climber jacket, these overshoes being of sufficiently heavy rubber to effectively insulate the lineman's feet against such

electric circuits as he may encounter in climbing a pole.

In order to protect the lineman's ankles, heavy rubber flaps 22 are formed on each side of the overshoe, being integral with or permanently attached thereto at their lower ends and extending up above the top of the overshoe.

These flaps 22 are bound against the ankle by means of the usual ankle strap 16 connected to the loop 15 upon the stirrup of the climber.

With this construction it will be seen that the entire feet and legs of the lineman are completely and effectively insulated from all portions of the metal climber so as to prevent a circuit from being grounded through the lineman's leg or foot to the pole.

I claim:

1. In combination with a lineman's climber having a shank portion with a stirrup at its

lower end to receive the lineman's foot, and an ankle strap connected to said stirrup, an insulation overshoe for the lineman's foot and insulation flaps upon the sides of the overshoe positioned to be bound against the lineman's ankle by said ankle strap.

2. In combination with a lineman's climber having a shank portion with a stirrup at its lower end to receive the lineman's foot, and a spur upon the outside of said stirrup, and an ankle strap connected to said stirrup, an insulation jacket of tubular form detachably, slidably mounted upon said shank portion and extending from the upper end thereof to a point near the end of the spur, an insulation overshoe for the lineman's foot and insulation flaps upon the sides of the overshoe positioned to be bound against the lineman's ankle by said ankle strap.

RUSSELL M. EVANS.
